UNITED STATES PATENT OFFICE.

JOHN EDWARD LEWIS OGDEN, OF LISCARD, ENGLAND.

DOUBLE-ACTING STEAM AND LIKE PUMP.

Application filed May 10, 1926, Serial No. 108,154, and in Great Britain October 14, 1925.

This invention refers to a new or improved construction of double acting steam or like pump, which in addition to other advantages arising from its construction, is 5 specially suitable for pumping hot or boiling liquids. In its application as a pump for hot or boiling liquids its chief use will be in connection with boiler feed pumps for returning water of condensation to the 10 steam boiler against boiler pressure, and in such connection the steam used in operating the pump may also serve to augment the heat of the feed water.

According to the invention, the pump comprises a cylinder closed at each end by a cylinder head and having a fixed central partition dividing the cylinder into two chambers, a piston in each chamber, a connecting rod passing through the said partition coupling the two pistons together, inlet and outlet valves for each chamber adjacent to the partition and inlet and outlet valves for each chamber adjacent to the cylinder heads. The invention further comprises ports in the cylinders to be covered and uncovered by the pistons, for controlling the valves for the steam or other fluid used for operating the pump, and where the pump is to be used as a steam pump for 20 boiler feed water purposes, the steam being admitted adjacent to the cylinder heads, further ports are provided in the cylinder, controlled by the pistons and connected for the transfer of the used steam at or near the 25 end of each stroke to the pump chamber charged by such stroke. The transference of the steam in this manner serves the dual purpose of completing the stroke and of employing the heat in the steam to heat the 30 feed water. A further feature of the invention consists in arranging the pump outlet at the upper part of the cylinder so that air or vapours are expelled first, giving quick priming and other advantages in 35 operation.

The accompanying drawings illustrate one form of feed water pump made in accordance with this invention in which:—

Fig. 1 is a longitudinal sectional elevation. 50 Fig. 2 is a cross-sectional elevation on line 2, 2, Fig. 1.

Fig. 3 is an external elevation of the pump.

Fig. 4 is a sectional detail view of the 55 pistons.

As shown, the cylinder *a* forming the body

of the pump, is formed on its under side with a cylindrical valve chamber *b*, the lower part of which is shaped to constitute a stand or base *c* for the pump. The cylinder *a* is 60 also formed with feed water inlet ports *d*, *d'* (not shown) at one side, and feed water outlet ports *e*, *e'* at the top. Non-return mushroom valves *d²* and *d³* (not shown) and *c²* and *c³* of the usual type are provided. The cylinder *a* is provided with cylinder heads *f*, *f'* and with a central partition *g* dividing the cylinder into two chambers, having their inlet port *d*, *d'* and an outlet port *e*, *e'* adjacent to the partition. 70 The partition *g* is formed with bosses *g¹*, *g²* and is bored centrally through the bosses. The cylinder *a* is provided with liners *a¹*, *a²* to facilitate construction, as for instance in the formation of ports, which will be referred to hereafter, and for easy replacement. Pistons *h*, *h¹* formed with a comparatively long skirt, are provided, one in each chamber of the cylinder, the pistons being connected together by a rod *h²* enclosed 80 by a sleeve *h³*, which latter is a sliding fit in the bore of the partition *g* and bosses *g¹*, *g²*.

The central portion of the cylindrical valve chamber *b* is separated from the cylinder *a* by an air space *b¹* which serves to 85 reduce the effects of conductivity, and the chamber is connected by ports *b²*, *b³* leading to the outer ends of the cylinder *a*. Outlet or exhaust ports *b⁴*, *b⁵*, are also provided in the valve chamber. Liners *b⁶*, *b⁷* are provided, one in each end of the valve chamber. The piston valve comprises two pistons *j* and *j'* connected by a rod *j²* to which they are each secured by gudgeon pin *j³*, *j⁴*. Each piston is formed with a waist *j⁵*, *j⁶* which 90 provides the passage for the exhaust steam. End covers *k*, *k¹* are provided for the valve chamber through which pass rods *j⁷*, *j⁸* secured in the heads of pistons *j* and *j'* on the end of which rods are arranged rubber 100 buffers *m*, *m¹* with adjusting nuts *m²*, *m³*, the buffers coacting with suitable bosses *k²*, *k³* formed on the covers *k*, *k¹*. For operating the piston valve, ports *n*, *n¹* are formed in the cylinder *a* so as to be uncovered by the 105 pistons *h*, *h¹* when at the inner ends of their strokes, such ports being connected by suitable piping *n²*, *n³* to the outer ends of the piston-valve chamber *b*.

The main steam inlet connection *o* is taken to the central portion of the piston valve chamber *b* and a common steam exhaust passage *o¹* and steam 110

outlet o^2 are provided below the valve chamber. Bye-pass passages o^3 , o^4 are cut in the valve chamber sleeves to allow the steam behind the valve pistons j and j^1 to leak to the exhaust passage o^1 at the end of its stroke.

For heating the feed water by means of the exhaust steam, ports p , p^1 are provided in the cylinder a , to be uncovered by the 10 pistons h , h^1 at the inner end of their stroke. Suitable piping p^2 , p^3 and control valves p^4 , p^5 are provided to connect these ports to the pump chamber of the opposite piston.

Where the pump is for pumping cold liquids it is desirable to check heat conduction, both to prevent heating of the liquid and condensation of the steam, and therefore the piston heads may be jacketed as shown at q^1 in Fig. 4, and such jacket may be an air 20 pocket, or may be filled with water, oil, asbestos, or any substance of low conductivity. In Fig. 4, the sleeve h^3 is dispensed with and the rod h^2 slides directly in the bosses g^1 , g^2 of the partition g , this enabling a greater 25 output to be obtained at a lower pressure, by reducing the differential area of the pistons.

In operation, assuming the pistons h , h^1 and piston valves j , j^1 to be in the positions 30 shown in Fig. 1, the steam entering the valve chamber b by the inlet o passes up the passage b^2 uncovered by the valve j into the cylinder a . The piston h is therefore caused to move to the right and in so doing reduces 35 the spaces between it and the partition g , causing the fluid therein to be forced out through the valve e^2 . At the same time the piston h^1 moves by reason of the connecting rod h^2 and in so doing draws in liquid 40 through the valve d^3 (not shown) into the pump space between the piston and the partition g while the steam space above the piston h^1 is open to exhaust through the passage b^3 , round the waist j^6 of the piston 45 valve to the exhaust passage o^1 and steam outlet o^2 .

As the left hand piston h nears the end 50 of its stroke it uncovers the port n in the cylinder and steam is admitted from the cylinder a directly to the head of the piston valve j forcing it across to the right. This movement of the piston valve opens the steam space above the piston h to exhaust and admits steam to the head of the piston 55 h^1 , and the return motion of the pistons h , h^1 takes place, at the end of which movement the port n^1 is opened, admitting steam to the head of the piston valve j^1 , and returning 60 it to the position illustrated, thus completing the cycle of operations.

When the ports p , p^1 are open, the steam in the cylinder (which at the end of the stroke is still at a considerable pressure) is admitted to the pump chamber of the opposite piston through the piping p^2 , p^3 and

valves p^4 , p^5 . Such transfer of steam has the effect of assisting the pistons h , h^1 to complete the stroke by introducing a pressure in the pump space, and also the heat in the steam is used to heat the contents of 70 the pump.

The construction and arrangement of the parts of the pump give many advantages as, for instance, in providing a high 75 output for the size and weight of the machine, in the elimination of glands and packings and the balancing effect of the pressures at the pistons avoiding the necessity of piston rings, in the lightness of 80 moving parts which assist in speeding up to give increased output, and in the arrangement of the pump valves which provide for expulsion of the gases first, and hence quick priming of the pump, and the 85 ability to deal with hot or boiling liquids.

What I claim is:—

1. A double-acting steam or like fluid pump comprising two cylinders arranged end to end, a partition separating the cylinders, a piston in each cylinder, a connecting rod joining the pistons and passing through the partition, valve controlled steam inlet and outlet means in the outer or power ends of the cylinders, valve controlled fluid inlet and outlet means in the inner or pump ends of the cylinders, a steam port in the wall of each cylinder adapted to be covered by the piston and to be uncovered thereby at the inner end of its stroke, as by a piston valve, for the passage and employment of exhaust steam from the cylinders, and valve operating means for the steam valves controlled by the movements of the pistons, as set forth.

2. A double-acting steam or like fluid pump comprising two cylinders arranged end to end, a partition separating the cylinders, a piston in each cylinder, a connecting rod joining the pistons and passing through the partition, valve controlled steam inlet and outlet means in the outer or power ends of the cylinders, valve controlled fluid inlet and outlet means in the inner or pump ends of the cylinders, a steam port in the wall of each cylinder adapted to be covered by the piston and to be uncovered thereby at the inner end of its stroke, as by a piston valve, valve controlled transfer passages from each such port to the pump end of the opposite cylinder, for the utilization of the exhaust steam in the cylinders and valve operating means for the steam valves controlled by the movements of the pistons, as set forth.

3. A double-acting steam or like fluid pump comprising two cylinders arranged end to end, a partition separating the cylinders, a piston in each cylinder, a connecting rod joining the pistons and passing through the partition, steam inlet and outlet means

- in the outer or power ends of the cylinders, a piston valve controlling such inlet and outlet means, valve controlled fluid inlet and outlet means in the inner or pump end of the 5 cylinders, a steam port in the wall of each cylinder adapted to be covered by the piston and to be uncovered thereby at the inner end of its stroke, and passages operably connecting such ports to the piston valve for the 10 passage of exhaust steam from the cylinders to operate the said piston valve, as set forth.
4. A double-acting steam or like fluid pump comprising two cylinders arranged end to end, a partition separating the cylinders, a piston in each cylinder, a connecting rod joining the pistons and passing through the partition, steam inlet and outlet means in the outer or power ends of the cylinders, a piston valve controlling such inlet and outlet means, valve controlled fluid inlet and outlet means in the inner or pump end of the cylinders, ports in the walls of the cylinders adapted to be covered by the pistons and to be uncovered thereby at the inner 20 end of their stroke, passages operably connecting such ports to the piston valve for the passage of exhaust steam from the cylinders to operate the said piston valve, and valve controlled transfer passages from such ports to the pump end of the opposite cylinder for the utilization of the exhaust steam in the cylinders, as set forth.
5. In a double-acting steam or like pump according to claim 1, pistons having a body or skirt longer than the stroke of the piston so as to cover the ports except when at the inner end of the stroke.
6. In a double-acting steam or like fluid pump comprising two cylinders arranged end to end, a partition separating the cylinders, a piston in each cylinder, a connecting rod joining the pistons and passing through the partition, valve controlled steam inlet and outlet means in the outer or power ends of the cylinders, valve controlled fluid inlet and outlet means in the inner or pump ends of the cylinders, a steam port in the wall of each cylinder adapted to be covered by the piston and to be uncovered thereby at the inner end of its stroke, as by a piston valve, for the passage and employment of exhaust steam from the cylinders, valve operating means for the steam valves controlled by the movements of the pistons; pistons having a body or skirt, and a boss on each side of the partition over which the body or skirt of the piston fits when at the inner end of its stroke so as to leave a relatively small compression space, as set forth.
7. A double-acting steam or like pump comprising two cylinders arranged end to end, a partition separating the cylinders formed with a central projecting boss on each side, a piston in each cylinder having a body or skirt longer than the stroke of the piston and adapted to fit over the boss when at the inner end of its stroke, a connecting rod joining the two pistons, a sleeve surrounding the connecting rod and passing through the partition and bosses, steam inlet and outlet ports at the lower and outer ends of each cylinder, a steam operated piston valve controlling such ports, valve-controlled pump inlet and outlet ports at the inner ends of the cylinders adjacent to the partition, the outlet ports being arranged in the upper portion of the cylinder, two further ports in the wall of each cylinder opening into the steam or power end thereof and with which the body or skirt of the piston acts to constitute a piston-valve, a valve-controlled transfer passage from one such further port in each cylinder leading to the pump end of the opposite cylinder and means connecting the other of such further ports to the piston valve for operating the valve, as set forth.
8. In a double-acting steam or like pump according to claim 7, in combination a piston jacketed with a heat non-conducting material, as set forth.

In testimony whereof I have signed my name to this specification.

JOHN EDWARD LEWIS OGDEN.
